Stanley W. Hayes Inventor
By his attorney J. S. Kimball

UNITED STATES PATENT OFFICE.

STANLEY W. HAYES, OF GENEVA, NEW YORK.

DESIGN FOR A DERAIL-BLOCK.

41,612.

Specification for Design.

Patented July 25, 1911.

Application filed November 28, 1908. Serial No. 464,990. Term of patent 14 years.

To all whom it may concern:

Be it known that I, STANLEY W. HAYES, a citizen of the United States, residing at Geneva, in the county of Ontario, State of New York, have invented a new, original, and ornamental Design for Derail-Blocks, of which the following, in conjunction with the accompanying drawing, forming a part hereof, is a full specification.

Figure 1 of the drawing is a top plan

view of a derail block of my design and Fig. 2 is a perspective elevation thereof.

I claim:

The ornamental design for a derail-block as shown.

STANLEY W. HAYES.

Witnesses:

H. F. NESTER,
M. M. HAMILTON.
